STEAM GENERATION.

1,230,990.

Specification of Letters Patent. Patented June 26, 1917.

Application filed June 23, 1911, Serial No. 635,002. Renewed November 18, 1916. Serial No. 132,207.

To all whom it may concern:

Be it known that we, WILLIAM ARTHUR BONE, resident of the University, Leeds, in the county of York, England, professor of applied chemistry, JAMES WILLIAM WILSON, resident of Carleton Works, Armley, Leeds, in the said county, gas-stove manufacturer, and CYRIL DOUGLAS McCOURT, resident of 13 Malwood road, Balham Hill, London, S. W., chemist, subjects of the King of Great Britain and Ireland, have invented new and useful Improvements in and Relating to Steam Generation, of which the following is a specification.

15 This invention relates to steam generators fired with liquid or gaseous fuel, and more particularly to that class of generator in which the fuel is burned in a combustion chamber and the products of combustion caused to pass through a number of boiler tubes traversing the body of water.

20 In applying this invention in practice the general plan on which fire tube boilers are at present constructed may be adhered to with the modifications hereinafter described.

According to this invention combustion takes place primarily in a combustion chamber situated within or in proximity to the shell of the boiler. The boiler tubes through which the products of combustion pass after leaving the combustion chamber are packed or charged with refractory material which is desirably in a fragmentary, granular or globular condition. Owing to this packing 35 a much higher heat transmission is obtainable per unit area of tube surface, and we are thereby enabled to reduce greatly the length of tube necessary to effect a given cooling of the furnace gases as compared 40 with the length heretofore generally in use.

In order to enable the furnace gases to overcome the resistance to flow exerted by the packing hereinbefore mentioned it is necessary to maintain a sufficient pressure difference between the furnace or combustion chamber and the chimney or off take. This pressure difference may conveniently be maintained by means of a fan or other suction appliance connected with the chimney or off take.

In order that the nature of this invention and the manner in which it is to be carried into effect may be clearly understood we

will describe it with reference to the accompanying drawings in which similar parts are indicated by the like letters in which

Figure 1 is a sectional elevation of a steam generator constructed according to our invention.

Fig. 2 is a sectional elevation of another form of steam generator constructed according to our invention.

Fig. 3 is a section showing a means of protecting the tube plate from excessive heating.

Figs. 4 and 5 represent a device for charging the tubes with granular material.

Referring to Figs. 1 and 2 A is a cylindrical boiler shell provided with an internal combustion chamber B and boiler tubes C. D is an offtake connected with a fan or other suction device not shown in the drawings and provided with a door E adapted to give easy access to the tubes for the purpose of charging with granular material as hereinafter described.

The combustion chamber B is provided with a door F preferably lined with fireclay or the like and which may be furnished with suitable openings for the introduction and lighting of one or more burners of any approved pattern for burning liquid or gaseous fuel. The said combustion chamber B may be lined with firebrick the outline of which is represented by the dotted line G for the purpose of rendering the combustion more complete. The air required for combustion will enter the combustion chamber through the openings in the door F being drawn in under the action of the fan or other suction device hereinbefore mentioned, and in the case of liquid fuel being also forced in by the injection of the compressed air or steam supplied to the liquid fuel burners.

The boiler tubes C are provided with fireclay or the like perforated plugs or ferrules H adapted to fit the tubes, and are packed with granular refractory material J as for example fire-brick crushed to such a size as will pass a sieve of one mesh to the linear inch, the finer material such as will pass a sieve of two meshes to the linear inch being rejected. The refractory material is retained in position at the other ends of the tubes by metallic grids or spiders K.

The fire-clay plugs or ferrules while serving to retain the granular material in the tubes, serve also to protect the tubes at their entrance ends from excessive heating and to direct centrally the hot gases into the granular material, and thus producing at, or about the place where the gases enter the granular material a temperature higher than would be obtained if the said gases were allowed free entrance over the entire open end of the tube.

The fire-clay plugs H are by preference so constructed that while a portion of their length tightly fits the tubes or can be made so to do by winding with asbestos cord or the like, the projecting part H² of the plug H will taper outwardly so as to retain in position a ganister or like lining L adjacent to the usual tube plate M which carries the tubes C and through which the projecting plugs pass. This is shown in detail in Fig. 3. Where however the tubes are too closely assembled to admit of the above arrangement, the projecting end of the plugs may be enlarged in such a manner as to cover or nearly cover the tube plate M when the plugs are assembled in position, the interstices if any being filled with fire-clay, ganister, or other refractory material of such a nature as to undergo but little shrinkage in burning.

The granular material with which the tubes are packed serves to greatly increase the heat transmission through the walls of the tubes to the surrounding water and in so doing appears to act in the following manner.

Part of the heat conveyed to the granular material is radiated thence to the walls of the containing tube, while at the same time the granular material serves to mix the gases in transit, continually deflecting gases from the center to the sides and vice versa, and repeatedly causing the hot gases to impinge on the walls of the containing tube. That part of the granular material which becomes incandescent serves to assist the combustion of any part of the fuel which on leaving the combustion chamber is not completely burnt.

We have found as the result of numerous experiments that the intensity of heat transmission through the walls of the tubes depends among other things on the size of the fragments with which the tubes are packed. The larger the fragments employed the longer will be the tubes necessary to effect a given cooling of the furnace gases. We have found that when the size of the fragments employed is such as will pass a sieve of one mesh to the linear inch but will not pass a sieve of two meshes to the linear inch a boiler tube 3 feet long and of three inches bore is sufficient to cool the furnace gases to a temperature at which they may conveniently be passed to a feed-water heater.

With regard to the packing of the tubes

with granular refractory material, when such tubes are arranged vertically the same may be evenly packed by merely dropping the granules therein, but where the tubes are arranged horizontally as in Fig. 1, this method will not apply. In order to pack the tubes evenly, we use a special tool, (see Figs. 4 and 5) comprising a disk T having fingers or projections T² near its periphery the disk being mounted on a convenient handle. The granular material is placed in the cube and pushed home by the disk, a rotatory or semi-rotatory motion being given thereto. This action is continued until the tube is filled.

In previous applications we have described apparatus for the generation of steam wherein are employed packed tubes provided with fire-clay plugs at their entrance ends, combustion in one case taking place in the packed tubes and in another case the packed tubes serving to utilize the heat from hot waste gases, and we wish it to be understood that we do not claim such arrangements *per se.*

What we claim as our invention is:—

1. Steam generating apparatus, comprising in combination with a boiler shell, a combustion chamber for the primary combustion of the fuel, a heating tube traversing the water space of the boiler and leading from the combustion chamber to a suction offtake to receive the combustion gases and unburned fuel from the combustion chamber, said tube containing refractory material whereby the transmission of heat to the water from the hot combustion gases passing through the tube is increased and the combustion within the tube of unburned fuel is promoted.

2. Steam generating apparatus, comprising in combination with a boiler shell, an internal combustion chamber for the primary combustion of the fuel, a heating tube traversing the water space of the boiler and communicating with the combustion chamber to receive the combustion gases and unburned fuel, said tube containing refractory material whereby the transmission of heat to the water from the hot combustion gases passing through the tube is increased and the combustion within the tube of unburned fuel is promoted.

3. Steam generating apparatus, comprising in combination with a boiler shell, a combustion chamber for the primary combustion of the fuel, a heating tube traversing the water space of the boiler and communicating with the primary combustion chamber to receive therefrom the combustion gases and unburned fuel, and means providing a restricted passage with a wall of refractory material between the primary combustion chamber and the tube, and said tube being packed with pieces of refractory material whereby the transmission of heat to the water from the hot combustion gases

passing through the tube is increased and the combustion within the tube of unburned fuel is promoted.

4. Steam generating apparatus, comprising in combination with a boiler shell, an internal combustion chamber for the primary combustion of the fuel, a plurality of heating tubes traversing the water space of the boiler and leading from the primary combustion chamber to a suction offtake to receive the combustion gases and unburned fuel from the primary combustion chamber, said tubes being packed with pieces of refractory material whereby the transmission of heat to the water from the hot combustion gases passing through the tubes is increased and the combustion within the tubes of unburned fuel is promoted.

5. Steam generating apparatus, comprising in combination with a boiler shell, an internal combustion chamber for the primary combustion of the fuel, a plurality of heating tubes traversing the water space of the boiler and extending through a tube sheet to communicate with the primary combustion chamber to receive the combustion gases and unburned fuel therefrom, said tubes containing refractory material whereby the transmission of heat to the water from the hot combustion gases passing through the tubes is increased and the combustion within the tubes of unburned fuel is promoted, perforated plugs of refractory material arranged in the ends of said tubes which extend through the tube sheet, said plugs having enlarged projecting ends, and a lining of refractory material for the tube sheet held by the enlarged ends of said plugs.

6. Liquid heating apparatus comprising in combination with a liquid receptacle, an internal combustion chamber for the primary combustion of fuel, a heating tube traversing the liquid space of said receptacle and communicating with the primary combustion chamber to receive the combustion gases and unburned fuel therefrom, said tube containing refractory material whereby the transmission of heat to the liquid from the hot gases passing through the tube is increased and the combustion within the tube of unburned fuel is promoted.

7. Liquid heating apparatus, comprising in combination with a liquid receptacle, an internal combustion chamber for the primary

combustion of fuel, a heating tube traversing the liquid space of said receptacle and communicating with the combustion chamber to receive the combustion gases and unburned fuel therefrom, and means providing a restricted passage with a wall of refractory material between the primary combustion chamber and said tube, and said tube containing refractory material whereby the transmission of heat to the liquid from the hot gases passing through the tube is increased and the combustion within the tube of unburned fuel is promoted.

8. Liquid heating apparatus, comprising in combination with a liquid receptacle, an internal combustion chamber for the primary combustion of fuel, a heating tube traversing the liquid space of the receptacle and communicating with the primary combustion chamber to receive the combustion gases and unburned fuel therefrom, and a centrally perforated plug of refractory material arranged in the inlet end of said tube and providing a restricted passage between the primary combustion chamber and the tube, and said tube being packed with pieces of refractory material whereby the transmission of heat to the liquid from the hot gases passing through the tube is increased and the combustion within the tube of unburned fuel is promoted.

9. Liquid heating apparatus, comprising in combination with a liquid receptacle, a combustion chamber for the primary combustion of fuel, a plurality of heating tubes traversing the liquid space of the receptacle and communicating with the primary combustion chamber to receive the combustion gases and unburned fuel therefrom, said tubes containing refractory material whereby the transmission of heat to the water from the hot gases passing through the tubes is increased and the combustion within the tubes of unburned fuel is promoted.

In witness whereof, we have hereunto set our hands, in the presence of two witnesses.
